Application October 26, 1939, Serial No. 301,459

9 Claims. (Cl. 108—8)

The present invention relates to roofing material and has particular relation to strip shingles composed of a felt base impregnated and covered with asphaltic material.

According to the invention each shingle strip, comprising a body portion with a plurality of tabs along its butt edge, may be made of constant thickness along any line from its bottom edge to its top edge, that is, from the butt edge to the opposite edge, but of varying thickness from one side edge to the opposite side edge, being of maximum thickness at the central portions of the tabs, and tapering to minimum thickness between adjacent tabs.

When laid upon a roof or other surface, the thick portions of one strip will nest with the thin portions of the strip of sub-jacent and super-jacent courses of shingle strips, with the result that a large portion of the thick, heavily coated parts of each shingle strip will be exposed, while the thin, relatively lightly coated parts of each strip will be covered by shingles of adjacent courses, thereby affording the protection and long wearing qualities of any heavily coated roofing material with a substantially minimum quantity of material and at low cost.

Another advantage to be obtained by this type of construction is that the exposed tabs, being of increased thickness, throw deeper shadow lines on the roof and thus present a more pleasing appearance than do the ordinary type shingles of uniform thickness; and at the same time, due to the nesting of the thick and thin portions of super imposed shingles, a substantially flat roof covering is provided. Furthermore, since each tab of the shingle strips is reinforced by a thickened portion or rib extending longitudinally thereof, any tendency of the exposed tabs to curl or to blow up in strong winds, is greatly reduced.

These and other objects and advantages will become apparent from the following description of the typical embodiment of the invention that is shown in the accompanying drawing, wherein:

Fig. 1 is a plan view of a strip shingle unit;

Fig. 2 is a transverse vertical section through the unit;

Fig. 3 is a fragmentary front elevational view showing forward edge surfaces of a pair of shingle units in nested relation; and,

Fig. 4 is a plan view showing a plurality of shingle units of adjacent courses as they would be laid upon a roof.

As shown in the drawing each shingle strip may consist of a body having serrated upper and

lower edges 12 and 13 with the recesses 14 in the upper edges in vertical alignment with tabs 15 upon the lower edges. The body is of substantially uniform thickness along any vertical line from bottom or butt edge 13 to the upper edge 12, but varies in thickness from one side edge 16 to the opposite side edge 17, being of maximum thickness in vertical bands 18 which extend from the central portions of recesses 14 to the central edge portions of tabs 15, and being of minimum thickness in vertical bands 19 at the side edges of the strip and in vertical alignment with recesses 21 in the lower edge 13 between tabs 15. The strip preferably tapers in thickness in vertical bands 22 between adjacent bands 18 and 19.

The strip shingles are preferably formed as follows: A web of roofing felt is impregnated and then heavily coated with asphalt or similar bituminous material. Then the coated web is scraped or rolled, or both, to produce contiguous thick, tapered, and thin bands longitudinally of the web, corresponding to bands 18, 22 and 19 in the finished shingles. Such bands may be produced by passing the heavily coated web under a scraper to remove excess coating material, and then between rolls having a contour complementary to the cross section of the shingle shown in Fig. 2.

30 The variations in thickness across the web may be produced by scraping the coating on the underneath side of the web to a uniform thickness, and varying the thickness of the coating on the top; the top being the side that receives the finishing 35 surfacing material and is the side exposed to the weather when the shingles are laid, or the variation in thickness can be obtained by maintaining a uniform thickness in the top layer of coating asphalt, and varying the thickness of the coating 40 on the underneath side, or both top and bottom coatings can be varied in thickness. In practice, the last named method has been found most satisfactory. In using any of the three methods, I find it preferable to keep the web of roofing felt 45 uniform in thickness.

Thereafter any suitable surfacing 23, such, for example as crushed slate, may be applied. Such material is either not applied to marginal portions 50 of the web, or is scraped therefrom after the surfacing operation, so that the side edge portions 24 of the finished shingle strips will be free of the surfacing material.

The finished web of roofing material may then 55 be cut transversely, along serrated lines, to pro-

duce individually the shingle strips with serrated upper and lower edges 12 and 13.

In laying the shingle strips upon a roof or other surface, the side edge portions 24 of adjacent strips of the same course are preferably overlapped, and strips of adjacent courses are staggered, as shown in Fig. 4, so that the tabs 15 of one course are in substantial alignment vertically with the recesses 21 of super-jacent and sub-jacent courses, resulting in a roof covering of hexagonal design when the tabs are of the form shown in the illustrated embodiment.

As shown in Fig. 3, the thick, thin and inclined portions of any one shingle nest with and complement the thin, thick and inclined portions, respectively, of an adjacent shingle. As shown in Fig. 4 the portions or bands 19 of each shingle strip, including the overlapping portions 24, are covered by adjacent courses of shingle strips, while almost the entire area of each thick portion or band 18 is exposed.

While the invention has been illustrated and described with reference to strip shingles, it will be understood that it may be applied to single shingles also, such a shingle having, for example, only one tab 15 and marginal portions 24 on each side thereof.

The drawing shows only one design of shingle, but it is to be understood that the invention lends itself to other designs known to the art, as for example the hexagonal strip shingle, and also square tab strip shingle; in fact, it can be applied to any strip or individual shingles that are laid in overlapping courses, wherein the overlying shingles are offset horizontally from the course below the distance of one-half the width of one tab.

It will be understood further that the embodiments of the invention illustrated and described herein are merely exemplary of the inventive principles involved, and that these principles may be otherwise embodied without departing from the spirit of the invention or the scope of the appended claims.

I claim:

1. In a strip shingle, a body having tabs along the lower edge thereof and corresponding recesses along the upper edge thereof, said body being of substantially uniform thickness between its upper and lower edges and of varying thickness between its side edges, being of maximum thickness at central portions of the tabs and of minimum thickness at portions between said tabs.

2. In a strip shingle, a body having tabs along the lower edge thereof, said body being of varying thickness from side edge to side edge, being thick in bands extending between its upper and lower edges through the central portion of said tabs, and thin in bands extending between said upper and lower edges through points between said tabs.

3. In a shingle, a body having a tab along the lower edge thereof and a corresponding recess along the upper edge thereof, said body being of

substantially uniform thickness between its upper and lower edges and of gradually varying thickness from side edge to side edge, being of minimum thickness adjacent the side edges thereof and increasing to a maximum thickness in a zone between zones of minimum thickness.

4. In a strip shingle, a body having tabs upon the lower edge thereof, said body being of varying thickness from side edge to side edge thereof, being relatively thin, adjacent the side edges thereof and at points between said tabs, and tapering to maximum thickness at points disposed substantially centrally of the tabs.

5. In a roof construction, a plurality of courses of shingles, the shingles of each course having spaced tabs and varying in thickness from side to side with the portions thereof adjacent the tabs relatively thick and the portions between said tabs relatively thin, the thick and thin portions of the shingles of one course being nested with the thin and thick portions, respectively, of shingles of an adjacent course.

6. In a roof construction of hexagonal design composed of courses of strip shingles having tabs at their lower edges with recesses between said tabs, said shingles being relatively thick in vertical bands extending between the upper and lower edges thereof in vertical alignment with central portions of said tabs, said shingles being relatively thin in vertical bands in vertical alignment with said recesses, the shingles of one course having the thick and thin bands thereof in register with the thin and thick bands, respectively, of shingles of an adjacent course.

7. In a shingle, a body having a tab on the lower edge thereof, said body including the tab tapering in thickness between the side edge portions of the shingle providing a vertically extending zone of maximum thickness, and the central portion of said tab being in said zone.

8. In a shingle, a body having a tab on the lower edge thereof, said body including the tab tapering in thickness from the side edge portions of the shingle toward the central portion thereof, being of minimum thickness in vertical zones adjacent the side edges thereof and of maximum thickness in a vertical zone between zones of minimum thickness, and the central portion of said tab being in said vertical zone of maximum thickness.

9. In a roof construction, a plurality of courses of shingles, each shingle having a tab on the lower edge thereof, and each shingle including the tab thereof varying in thickness from side to side of the shingle to provide along each course alternate vertical zones of greater and lesser thickness, the central portion of the tab being in the zone of greater thickness, the thick and thin zones of the shingles of one course being nested with the thin and thick zones, respectively, of shingles of an adjacent course, and said tabs being exposed and overlying the thin zones of a subjacent course of shingles.
